UNITED STATES PATENT OFFICE

97,813

DESIGN FOR A CANDLE STICK

Lurelle Guild, Noroton, Conn., assignor to Kensington, Incorporated, New Kensington, Pa., a corporation of Pennsylvania

Application April 20, 1935, Serial No. 56,483

Term of patent 3½ years

To all whom it may concern:

Be it known that I, Lurelle Guild, a citizen of the United States, residing at Noroton, in the county of Fairfield and State of Connecticut, have invented a new, original, and ornamental Design for a Candle Stick, of which the following is a specification, reference being had to the accompanying drawing, forming a part thereof.

Fig. 1 is a side view, and Fig. 2 is another side view, of a candle stick embodying my new design.

The principal feature of this design is the configuration of the base and the adjacent section

of the upright portion of the candle stick, which is ornamented as shown. The shape of the upper end of the candle stick is also a feature of the design. In the design the decoration near the base is of a different color than the remainder of the candle stick. This feature may be obtained by making the decorative element of brass and the remainder of the candle stick of aluminum, for example.

I claim:

The ornamental design for a candle stick, as shown and described.

LURELLE GUILD.
